UNITED STATES PATENT OFFICE.

ROBERT C. PALICKI, OF TOLEDO, OHIO.

WORK GLOVE.

Application filed May 7, 1927. Serial No. 189,513.

This invention relates to gloves, but more particularly to work gloves for use in wet places or around chemicals.

It is a desideratum that a work glove be produced having the following three characteristics: water and chemical proof, that is, that the material of the glove be impervious to water and chemicals so that the efficiency of the workman is not impaired when working under such conditions; durable and serviceable over an extended period of time, that is, that the glove will withstand the hard usage to which it is subjected for a considerable time, but is sufficiently light and flexible so that the fingers and hand may be used to substantially the same advantage as without the glove; and inexpensive, this being an important characteristic, so that the glove is within the purchasing power of the ordinary workman. So far as I am aware, no glove has heretofore been produced which satisfactorily meets the above requirements. It has been found that gloves which are chemical and water proof and are at present in use, will not withstand the hard usage or are so expensive as to be prohibitive to the ordinary workman.

Numerous attempts have been made to solve the above problem and provide a glove which is satisfactory in all respects. For example, a glove has been devised with a rubberized palm and canvas back. While the palm is water-proof the back is not; furthermore, the water-proof palm is not sufficiently strong and durable to last but a short period of time under the hard usage to which the glove is subjected. Such glove is, therefore, unsatisfactory and inefficient, and does not fill the long-felt need. Other attempts along this line have been made, but none of them have been crowned with success.

An object of this invention is to produce a new and improved work glove which is simple in construction, durable over an extended period of time, and water and chemical-proof. Other objects will hereinafter appear.

By way of illustration and not of limitation the invention is shown on the accompanying drawing, in which:

Fig. 1 is an elevation of the front side of the glove; Fig. 2 is an elevation of the back side of the glove, and Fig. 3 is an enlarged

transverse section on the line 3-3 of Fig. 2. The illustrated embodiment of the inven-

tion comprises a work glove having a back 1 and front 2, the back being of a relatively thin and flexible textile material 3, such as canton flannel. The outer portion of the material 3 is rubberized to provide a water and chemical proof material, and the rubberization may be accomplished by coating the material with a rubber solution, and frictionally or otherwise forcing this solution into the pores of the material. Thereafter, by vulcanizing the material, a water and chemical-proof coating is produced. The material is so treated that only the outer portion is rubberized so that the soft 70 fleecy nap 4 is left on the inside of the material. This presents a pleasing and comfortable feeling to the wearer of the glove, as will readily be understood.

Although the material may be cut according to different patterns, the fingers in the glove shown on the drawing are individually cut and sewed together, as indicated at Fig. 3, with the rubberized portions of the material in contact with each other, the 80 stitching 5 securing the parts together, being protected from water and chemicals by the rubberized outer portion of the material.

The front of the glove is in part made of textile material 6 similar to the material 3 hereinbefore described. As above pointed out, the rubberized material is relatively thin, and therefore is not of sufficient strength to wear for an extended period of time, in fact, this material wears through 90 very readily, and is absolutely impractical for workmen, as for example, locomotive engineers, where gloves are subjected to exceedingly hard usage.

I have found that by covering the rubberized material 6 on the front of the glove with a layer 7 of relatively thick heavy, but flexible wear-resistant material, such as leather, an exceptionally satisfactory and efficient glove is provided. The material 7 100 not only covers the palm of the glove, but also the wearing surfaces of the thumb and fingers.

By this construction it is manifest that a durable wearing surface is provided, but further than this a glove which is water-proof and chemical-proof throughout is provided. Both the back and front are protected against the penetration of liquid and chemicals; also the front of the glove, or 110 the wearing surface, is thoroughly protected so that the life of the glove is greatly en-

hanced, and the practicability thereof is materially increased.

The front of the glove has, in fact, three layers, an outer wearing surface or layer, a water-proof layer, and an inner layer of soft material comfortable to the wearer. A glove of this description may be inexpensively manufactured so that the selling price to the workman is reduced to a minimum, 10 bringing the glove within his purchasing power.

In order effectively to secure the back 1 to the front, the material 3, material 6 and leather covering 7 are folded inwardly at 15 the side edges, and extending through these inturned edges is stitching 8 which serves as a common securing means for the several parts. This is not only advantageous in reducing the cost of manufacture, but also 20 protects the inside of the glove against the entrance and penetration of liquids and chemicals, as well as protecting the stitching against liquids and chemicals, which would otherwise weaken the connection.

25 A cuff 9 of rubberized material may be sewed to the front and back of the glove, as shown, and if desired, the gauntlet 9 may form a continuation of the front and back, but this construction forms no part of the 30 present invention.

It will be seen that I have provided a work glove which is admirably adapted for the purpose. This glove is inexpensive, light, flexible, durable over an extended period of 35 time, and water and chemical-proof, thereby

satisfactorily meeting the requirements of the trade primarily enumerated.

While I have shown and described a construction which is the best form known to me at the present time, numerous changes 40 in details of construction, choice of materials and arrangement may be effected without departing from the invention as expressed in the following claim.

What I claim as new and desire to secure 45 by Letters Patent is:

A work glove embodying a relatively thin flexible back formed of rubberized material, a relatively thick leather front, a backing comprising a separate ply of the same material of which the back is formed having a rubberized face contacting with the inner face of the leather front, the marginal edges of the thick leather front and the rubberized backing thereof and the rubberized back 55 being each turned inwardly so that the in-turned edges of the thick leather front are interposed between the rubberized back and the rubberized backing of the front, and stitching extending transversely through 60 each of the said in-turned edges of the leather front, the rubberized backing thereof and the back whereby to provide a three-ply joint and whereby the leather provides anchorage 65 for the stitching and the rubberized back provides a waterproof joint adjacent the line of the stitching.

In testimony whereof I have hereunto signed my name to this specification.

ROBERT C. PALICKI.
